UNITED STATES PATENT OFFICE

EDWARD K. BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

MANIFOLDING DEVICE

Application filed September 12, 1929. Serial No. 392,044.

This invention relates to manifolding pads and sets of manifolding leaves, and has for its object the provision of a simple and practical construction of manifolding pad wherewith assurance of manifold copying is bettered, and wherewith manifold copying and distribution of record leaves after separation from the pad is facilitated and promoted.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawing, in which:

Fig. 1 is a perspective view of a manifolding pad embodying the invention, and

Fig. 2 is a perspective view diagrammatically illustrating one of the sets of record leaves and its intervening carbon sheet.

Referring now more specifically to the drawing, the pad illustrated in Fig. 1 is composed of a plurality of relatively superposed sets of record leaves, each set including an intervening carbon sheet. One such set, detached, is illustrated in Fig. 2, wherein the numeral 1 indicates an original record leaf, 2 a duplicate record leaf, and 3 the intervening carbon sheet. In practice only the bottom face of the carbon sheet 3 is coated with a transfer material, as for instance illustrated at 4, although it is to be understood that a double-faced carbon sheet may be utilized if desired.

Considering the arrangement of one set, as illustrated in Fig. 2, it will be apparent that inscription made upon the top face of the original record leaf 1 will be copied on the duplicate record leaf 2 by reason of the intervening carbon sheet 3. Each of the record leaves 1 and 2 is provided with a printed form, as for instance a bill form, indicated at 5 and 6.

For the purpose of retaining printed forms 5 and 6 in superposed registry with each

other, and for making a convenient and practical pad, the several sets of leaves and sheets 1, 2 and 3 are superposed relatively to each other and bound together by staples 7. It is to be understood, however, that other practical ways of binding the sets together in pad form may be utilized.

The record leaves 1 and 2 are included in an integral, folded record sheet, the fold being indicated at 8, and the sheet is preferably weakened along this fold as indicated by the dotted lines 9. The two outer ends 11 and 12 of the fold sheet are superposed on each other and one is bound at the stub of the pad by the staples 7. Also these folds are adhesively connected to each other as by a transverse line of paste 13, so that the two folds or leaves 1 and 2 of the record sheet are connected together at the portion 13 and at the fold 9, which portions are spaced apart longitudinally of the leaves, a pocket being thus provided between the leaves. In this pocket lies the carbon sheet 3. Adjacent the stub of the pad the stapled leaf 2 has a weakening line 14, for ready detachment from the stub, and in case the upper leaf 1 is extended beyond this weakening line as shown to form the stub 11, a weakening line 14 will also be formed in the upper leaf preferably in substantially superposed register with the lower line 14. It will be noticed that the portions connected by the paste lie outside the weakening lines 14.

In the present embodiment the carbon sheet 3 lies relatively loosely in registry position in the pocket and between the folds of the folded sheet. The carbon sheet 3 thus lies in manifolding relation in the pocket, and is retained in such relation and restrained to registry position by the connected portions 13 and 8 of the folded record sheet. The carbon sheet is sufficiently long so that although it lies loosely in the pocket, its opposite ends approach the line of paste 13 and the fold 8.

In use, inscription on the original leaf 1 of the topmost set of the pad will be transferred in registry relation to the bill form on the duplicate leaf 2, by the intervening carbon sheet 3. After inscription, the leaves

- 1 and 2 may be grasped between the thumb and finger and parted from the stub along the weakening lines 14. This parting, however, does not part the leaves 1 and 2 from each other along the paste line 13, and the result is that after parting of the set from the stub, the carbon sheet 3 is retained in manifolding relation to the original and duplicates 1 and 2, so that subsequent manifold 5 inscription may be effected with assurance that the carbon sheet is in manifolding position. It will also be noted that each manifolding set or unit may be separately detached from the pad before inscription, 10 whereupon it may be written upon by inserting it into a writing machine. After inscription has been completed the ends of the folds, or leaves, 1 and 2 may be parted from each other at the paste line 13 and at the 15 weakened line 9 as will now be understood. After a set is parted from the stub the parted end of the set will afford a relatively stiff member or handle by which the parted set may readily be manipulated. 20
- 25 It is to be understood that the pad is composed of a series of superposed sets of record leaves with their intervening carbons. In order that inscription made on one set may not be copied on to underlying sets, a stop 30 plate 15 is provided. The numeral 15 indicates a stop plate, the purpose of which is to underlie the undermost record leaf of a set so as to prevent copying on the lower set by the inscription being made upon the upper set. 35 The stop plate 15 may consist of a relatively heavy manilla or cardboard leaf of proper consistency to prevent copying therethrough. As illustrated, the plate 15 is embodied in a flexible sheet of relatively heavy manilla 40 paper which is of sufficient length to extend around the front end of the pad as at 16, and underlie the pad to provide a backing portion 17 which may be secured to the bottom of the pad through the intervention of the staples 7. 45 After one set has been inscribed, the stop plate 15 may be inserted between the next two underlying sets prior to inscription upon the upper set of the latter. 50 Since certain changes may be made in the above article and different embodiments of the invention could be made without departing from the scope thereof, it is intended that all matter contained in the above description or shown in the accompanying drawing shall 55 be interpreted as illustrative and not in a limiting sense. 110
- Having described my invention what I claim as new, and desire to secure by Letters Patent, is:
- 60 1. A manifolding set including original and duplicate record leaves in superposed manifolding relation with each other, transversely disposed attachments between said record leaves adjacent the opposite ends 65 thereof so as to provide a pocket between said 120 leaves closed at its opposite ends by said attachments, one of said leaves extending beyond said attachment to form a binding stub for the set, at least one of said leaves having a weakened severance line positioned between said stub and the adjacent said attachment whereby the two leaves may be detached from the stub as a self-contained unit with said pocket thereof intact, and a transfer sheet within said pocket positioned in manifolding transfer relation with one of said record leaves. 70
2. A manifolding set including a record sheet transversely folded to bring parts thereof into superposed manifolding relation to provide original and duplicate record leaves in superposed manifolding relation with each other, an attachment between said record leaves adjacent the ends thereof remote from the fold so as to provide a pocket between said leaves closed at its opposite ends respectively by said fold and said attachment, one of said leaves extending beyond said attachment to form a binding stub for the set, and at least one of said leaves having a weakened severance line positioned between said stub and said attachment whereby the two leaves may be detached from the stub as a self-contained unit with said pocket thereof, said record leaves being free from attachment with each other along adjacent edges to provide an entrance opening for the pocket, and a single transfer sheet lying loosely within said pocket in manifolding relation with said record leaves and being positioned for access through said entrance opening. 80
